CLAIM

The ornamental design of a gymnastic machine, as shown and described.

DESCRIPTION

FIG. 1 shows a bottom view of a gymnastic machine according to our new design in a first configuration;

FIG. 2 shows a front view of the gymnastic machine shown in FIG. 1;

FIG. 3 shows a top view of the gymnastic machine shown in FIG. 1;

FIG. 4 shows a righthand side view of the gymnastic machine shown in FIG. 1;

FIG. 5 shows a rear view of the gymnastic machine shown in FIG. 1;

FIG. 6 shows a lefthand side view of the gymnastic machine shown in FIG. 1;

FIG. 7 shows a perspective view of the gymnastic machine shown in FIG. 1;

FIG. 8 shows a bottom view of the gymnastic machine according to our new design in a second configuration;

FIG. 9 shows a front view of the gymnastic machine shown in FIG. 8;

FIG. 10 shows a top view of the gymnastic machine shown in FIG. 8;

FIG. 11 shows a righthand side view of the gymnastic machine shown in FIG. 8;

FIG. 12 shows a rear view of the gymnastic machine shown in FIG. 8;

FIG. 13 shows a lefthand side view of the gymnastic machine shown in FIG. 8; and,

FIG. 14 shows a perspective view of the gymnastic machine shown in FIG. 8.
